MANIFOLD

Walter S. Smith, Quincy, Mass., assignor to Shore Corporation, Dover, Del., a corporation of Delaware

Application March 28, 1932, Serial No. 601,649

15 Claims. (Cl. 123—52)

This invention relates to fuel supply means for internal combustion engines and the like which employ gasoline, kerosene, or other liquid fuels, and particularly to the manifolds therefor. The invention has for its principal object, the provision of means which assist in the formation of the fuel-air mixture and deliver said mixture to the cylinders in like quantity, quality, and in proper condition for efficient and trouble free engine performance, particularly with kerosene or even heavier hydrocarbon fuels. Further objects of the invention are to provide an improved intake manifold suitable for use with two or more carburetors as is common for some engines, for example marine engines, and to provide an improved exhaust-heated intake manifold for internal combustion engines with or without a water-cooled jacket for such exhaust-heated manifolds.

Referring to the drawing, which illustrates a preferred embodiment of my invention:—

Fig. 1 is a view showing my improved manifold as applied to a six cylinder engine of marine type, the manifold itself, being shown principally in horizontal cross section with certain minor portions thereof, shown in plan;

Fig. 2 is a vertical cross sectional view of the complete manifold taken on the line 2—2 of Fig. 1;

Fig. 3 is a vertical cross sectional view taken on line 3—3 of Fig. 1; and

Fig. 4 is a perspective view showing a connecting bushing as employed in the manifold of Figs. 1—3.

Referring to the drawing in which like numerals represent like parts.—

The intake manifold, in this embodiment for a six cylinder marine engine, consists of three riser or inlet pipes, generally designated at 2, which lead from the three carburetor portions 3 (the complete carburetors not being shown) and connect respectively with the header portions 4. Each of said header portions connects with outlet branches, generally designated at 6, leading from said header portions to the intake valves 7 of the various cylinders. The headers 4 are shown connected with each other as at 8 so that they in effect become a single long header with the opposite ends thereof closed by plugs 9. The connecting telescopic joints 8 are fitted to allow for expansion and contraction due to differences in temperature, and to permit slight relative movement of the headers 4, though the sliding joints are not essential and the entire length of header may be formed integral. The headers as shown, though connected as described, are par-

tially separated from each other in their bore by annular baffles 10 having holes 12 therethrough which permit the flow of mixture between the header sections as hereinafter described. These baffles are an important factor in the operation of my manifold in that they effectively minimize the pulsations or surges which frequently interfere with proper multi-cylinder engine operation and performance, particularly at some one speed range. At the same time, the baffles sufficiently permit the flow of mixture therethrough (in response to the suctions of cylinders separated thereby) so as to cause a more uniform flow through each of the carburetors and thus avoid a complete or troublesome stoppage of the flow through any one of said carburetors, which would occur but for the passage in the baffles. Thus my manifold, by reason of the baffles, eliminates trouble due to manifold surging and provides the desired constant flow through the carburetor system. Actual engine operation has shown that the entire range of engine speeds may be covered without troublesome manifold surging or carburetor stoppage. Both of these features therefore, serve to provide more uniform engine operation and to secure more uniform distribution of the fuel-air mixture to the respective cylinders. The specific construction as shown is that applied to a heavy duty six cylinder marine engine in which it is desired to burn kerosene and other hydrocarbon fuels somewhat heavier than ordinary present day gasoline. For such purpose, the intake manifold as described, is provided with a novel exhaust-heated portion consisting of an exhaust passage 14 surrounded by a cylindrical jacket 16 and, since the manifold is designed for marine use, the exhaust jacket is equipped with a surrounding cylindrical water jacket 18, whereby the exterior of the manifold is maintained by circulating water at the desired temperature. The exhaust gases are conducted to the space 14 through pipes generally designated at 20 leading from the Siamesed exhaust valves 21 of the engine, the exhaust gases being brought into contact with deflectors 22 at each T of the headers 4. The size or mass of the deflectors is determined by the degree to which it is desirable or necessary to heat the fuel-air mixture. When the larger heat transfer is required, dependent upon the fuel and the load and speed conditions, the projection of the deflectors may be reduced in size or altogether omitted so that the exhaust gases impinge squarely upon the outside of the header 4, the curved exterior plane thereof being more nearly transverse to the exhaust gas flow than would

the sides of the deflectors. As will be seen from the drawing, the exhaust-gases are free to circulate within the jacket 14 and pass therefrom through the outlets 24 into the usual exhaust line (not shown). In so passing through the jacket 18, the gases effectively heat the intake manifold particularly adjacent to and opposite the riser pipes 2, so that the incoming mixture is projected against an opposing heated wall at right angles to its direction of flow. In this manner the fluid particles which tend to be thrown from the moving mixture stream are brought into contact with the top of the T which is normally so hot that such particles cannot cling thereto and, consequently, are carried left and right in accordance with the induction cycle of the engine. In order to care for the differences in temperature in the manifold, as just described, I preferably cast the exhaust and water jackets 16 and 18 respectively, out of an alloy of aluminum or other suitable metal having a relatively high heat conductivity. The temperature of these jackets is of course always less than that of boiling water while the temperature of the header portion of the manifold of the type shown may be considerably higher, but, since the header portion of the manifold is made from iron or other material having a co-efficient of expansion (due to temperature) materially less than the surrounding aluminum jacket, the temperature difference does not result in destructive expansion.

The header portions 4 of the manifold shown are held in place by bushings 26 (see Fig. 4) flanged at one end 26a and threaded at the other 26b, so that the bushings when threaded into the correspondingly threaded portions of the header, serve to hold the same in position. It will be seen from the drawing that each riser portion 2 includes one of said bushings as well as each intake branch 6 so as to complete the induction system.

Though the manifold as shown is for a six cylinder engine, the invention is equally useful for a four or eight cylinder engine having two or four carburetors respectively. The spacing and the relations of the inlet conduits and cylinders are, in such cases, essentially the same for each two cylinder unit or pair. It is also contemplated that the manifold of this invention may be employed with down-draft carburetors in which case the inlet conduits lead downwardly into the header 4.

Having described my invention, what I wish to secure by Letters Patent is:

55. 1. In an inlet manifold for a multi-carburetor engine having cylinders arranged in line, a lateral header having pairs of outlet branches leading therefrom and separate inlet conduits leading thereto from the respective carburetors, each of said inlet conduits entering the header between the members of a pair of said outlet branches, said header being provided with means between pairs of outlet branches to check surging of fuel therein.
60. 2. In an inlet manifold for a multi-carburetor engine having cylinders arranged in line, a lateral header having pairs of outlet branches leading therefrom and separate inlet conduits leading vertically thereto from the respective carburetors, each of said inlet conduits entering the header between the members of a pair of said outlet branches, said header being provided with means between pairs of outlet branches to check surging of fuel therein.
65. 3. In an inlet manifold for a multi-carburetor

engine having cylinders arranged in line, a lateral header having pairs of substantially horizontal outlet branches leading therefrom and separate inlet conduits leading vertically thereto from the respective carburetors, each of said inlet conduits entering the header midway between the members of a pair of said outlet branches, said header being provided with means between pairs of outlet branches to check surging of fuel therein.

4. In an inlet manifold for a multi-carburetor engine having cylinders arranged in line, a lateral header having pairs of outlet branches leading therefrom and separate inlet conduits leading thereto, each of said inlet conduits entering the header midway between the members of one of said pairs, said header being provided with means between pairs of outlet branches to check surging of fuel therein.

5. In an inlet manifold for a multi-carburetor engine, a header having pairs of outlet branches leading therefrom and separate inlet conduits leading thereto, each of said inlet conduits entering the header between the members of one of said pairs, means providing said header with a restricted opening positioned between said pairs, and in spaced relation to the header walls.

6. In an inlet manifold for a multi-carburetor engine, a header having pairs of outlet branches leading therefrom and separate inlet conduits leading thereto, each of said inlet conduits entering the header between the members of one of said pairs, means providing a permanent restricted opening in said header and between said pairs, said opening being located in spaced relation to the header walls.

7. In an inlet manifold for a multi-carburetor engine, a header having pairs of outlet branches leading therefrom and separate inlet conduits leading thereto, each of said inlet conduits entering the header between the members of one of said pairs, a perforated baffle positioned in said header between said pairs, and effective to check surging of fuel in the header, said baffle being constructed to position the perforation thereof in spaced relation to the header walls and to present sharp corners terminating abruptly about the perforation.

8. In an inlet manifold for a multi-carburetor engine, a header permanently open from end to end and having pairs of outlet branches leading therefrom and separate inlet conduits leading thereto from the respective carburetors, each of said inlet conduits entering the header between the members of a pair of said outlet branches, said header being provided with stationary baffles between pairs of outlet branches to check surging of fuel therein.

9. An intake manifold having a series of pairs of outlet branches connected to the inlet ports of an engine with each of said branches feeding but one cylinder, a lateral header permanently open from end to end and connected to each of said branches, baffles between said pairs of outlet branches, a plurality of inlet pipes each connected at one end to a carburetor and at its other end to said header between the members of each pair.

10. A manifold for a multi-cylinder multi-carburetor internal combustion engine having a header permanently open from end to end, pairs of outlet branches from the header to the cylinders, partial partitions in said header between pairs dividing it into sections, each section having an inlet conduit from a carburetor.

11. A manifold for a multi-cylinder multi-car-

5 buretor internal combustion engine having a header permanently open from end to end, pairs of outlet branches from the header to the cylinders, annuli in said header between pairs dividing it into sections, each section having an inlet conduit from a carburetor.

10 12. An intake system having a plurality of manifold header portions, a pair of outlet branches leading from each of said header portions, an inlet pipe entering each header portion between the members of the pair of outlet branches therefrom and a restricted permanently open conduit between adjacent header portions.

15 13. An intake system for a multi-cylinder internal combustion engine, comprising an intake manifold having a header composed of a plurality of aligned tubular sections, a jacket therefor adapted to be heated by the exhaust gases, telescoping connections between adjacent sections of said header, stationary baffles located approximately within the respective telescoping connections, and effective to check surging of fuel in the header, outlet branches leading from said header to the cylinders and an inlet pipe to

20 25 said header.

14. An intake manifold for an internal com-

bustion engine having a header, outlets from the header leading to the intake ports of the cylinders, conduits leading into said header, an exhaust manifold having a wall with portions common to said header, outlet passages to said exhaust manifold from the exhaust ports of the cylinders, and projections on said common wall portions approximately adjacent the junction points of said conduits and header and extending into said exhaust manifold opposite said exhaust outlet passages.

10 15 16. An intake manifold for an internal combustion engine having a header, outlets from the header leading to the intake ports of the cylinders, conduits leading into said header, an exhaust manifold having a wall with portions common to said header, outlet passages to said exhaust manifold from the exhaust ports of the cylinders, and projections on said common wall portions approximately adjacent the junction points of said conduits and header and extending into said exhaust manifold opposite said exhaust outlet passages said projections being beveled to deflect the impinging exhaust gases.
